UNITED STATES PATENT OFFICE.

SHIERFIELD G. MYERS, OF FREEPORT, NEW YORK, ASSIGNOR TO THE SPERRY GYROSCOPE COMPANY, OF BROOKLYN, NEW YORK, A CORPORATION OF NEW YORK.

DRIVING MEANS FOR SHIPS' GYROSCOPES.

Application filed September 11, 1922. Serial No. 587,351.

To all whom it may concern:

Be it known that I, SHIERFIELD G. MYERS, a citizen of the United States of America, residing at Freeport, Long Island, in the county of Nassau and State of New York, have invented certain new and useful Improvements in Driving Means for Ships' Gyroscopes, of which the following is a specification.

- 10 This invention relates to gyroscopes for ships of the type shown in Patent No. 1232619, dated July 10th, 1917, to Elmer A. Sperry for ship stabilizing and rolling apparatus. As set forth in said patents, gyroscopes of this type may be used either for stabilizing a ship or for rolling it. In such apparatus the precessional movement of the main gyroscope is controlled by a precession engine or auxiliary gyroscope. When 20 the main gyroscope is employed as a stabilizer, its natural precessional movement is accelerated and retarded at proper times by the precession motor. However, when the main gyroscope is employed to roll the ship, 25 it must be precessed in the opposite direction, that is, against its normal precessional movement, due to the ship's roll. It is obvious that with the main gyroscope running at the same high speed, it would require a 30 great deal more power to roll the ship than to stabilize it. In fact, it has not heretofore been found practical to precess the main gyroscope oppositely to roll the ship while the main gyroscope was running at its high 35 speed, owing to the large power required by the precession motor. It is also the present practice to supply power for both the spinning motor and the precession motor by a single turbo-generator set, so that in order 40 to obtain full voltage for the precession motor, when rolling the ship, full voltage would also be supplied the spinning motor. In the past, this condition has been met in a manner by opening the circuit of the spinning 45 motor for the main gyro rotor, and permitting the rotor to coast, and after its speed has reduced somewhat, precessing it by means of the precessional motor. It is of course understood that the main gyroscope 50 rotor commences to decelerate from the moment the spinning motor circuit is opened, but this deceleration is further ac-

celerated by the unnatural precessional movement of the main gyroscope when rolling the ship, in which case it is, of course, 55 performing the necessary work to roll the ship, in other words, the rotor is being retarded by its own gyroscopic forces. In practice, it is found that these factors, together with the bearing losses, reduce the 60 rotor speed several hundred R. P. M. in a very short time. The result is that in view of the decreasing speed of the main gyroscope rotor, an uneven rolling is obtained, also, the speed of the rotor may be reduced 65 beyond the necessary or desired limit. The period during which the main gyro may so operate is therefore limited, and it may be necessary to again close the rotor circuit to accelerate the rotor, thereby again varying 70 the periodicity of the ship's rolling. While an even roll is highly desirable in all classes of marine vessels, it is essential for naval vessels equipped with modern gun-fire control, in which system the angle through 75 which the ship rolls is a factor considered in aiming the guns, and their firing is timed to take place at certain angles. In addition to these undesirable results, a further loss in power and time is experienced when it is 80 desired to again operate the main gyroscope at high speed as a stabilizer.

In order to overcome these objections, I have provided the main gyroscope with a multiple speed alternating current induction motor, in which while normally the high speed is employed, either of the speeds may be employed for stabilizing the ship and the low speed is employed for rolling the ship. In the latter case, a fraction of 90 the full speed is preferably employed, say $\frac{1}{3}$ or $\frac{1}{4}$ thereof.

When supplying power to the system described by an alternating current turbo-generator, which is the most efficient means and that generally employed, it is imperative that the turbo-generator be operated at three-quarters to full speed, preferably, the latter, in order that the generator, which also supplies power for precession, shall deliver current at full voltage to the precession motor. By the arrangement outlined, current at full voltage may at all times be supplied to the precession motor, and at the

same time, the same current and voltage, or a fraction thereof may be supplied to the main gyroscope spinning motor.

This arrangement also permits the fractional speed to be employed when starting the main gyro, an obvious advantage.

My invention further permits the use of the main gyroscope rotor fly-wheel effect in averaging the load on the turbine during precession. At the instant the precession motor starts, the heavy starting current will cause a reduction in the alternating current to the spinning motor, and at the end of the precession movement, the precession motor 15 may be used as a dynamic brake, which will increase the current to the spinning motor, that is, I employ the energy utilized in braking the precession of the gyroscope when operated to roll the ship to assist in driving 20 the rotor of the main gyroscope, and further utilize the energy of said rotor to aid the precession motor whenever the peak load on the motor occurs. This of course was not possible heretofore when the apparatus was 25 used to roll the ship, since the circuit to the main gyroscope spinning motor was open at such times.

My invention will be better understood from the following description taken in connection with the accompanying drawings, and its scope will be pointed out in the appended claims.

In the drawings, illustrating what I now consider a preferred form of my invention, 35 Fig. 1 shows the several units of the system in elevation, with parts indicated in dash lines, in operative relation and a wiring diagram of the several connections and control devices therefor, and

40 Fig. 2 is a wiring diagram of one type of the main gyroscope spinning motor.

Referring now to the drawings in which 1 represents an alternating current turbo-generator, 2 the main gyro, 3 the precessional motor and 4 the auxiliary or control gyro diagrammatically illustrated. The main gyro 2, is provided with a spinning motor, diagrammatically indicated by dash lines 5 in Fig. 1, having two sets of windings 6, 7, diagrammatically illustrated in Fig. 2. These windings are respectively arranged to give the spinning motor two speeds, a high and a low speed both of which may be employed to spin the main gyro 55 rotor when it is being used as a stabilizer, and the latter of which is employed to spin said rotor when the main gyro is employed to roll the ship. It is of course understood that the main gyro is mounted in proper supports crosswise on the ship as indicated by the arrow representing the fore and aft line of the ship. The two speed spinning motor may be of any conventional type, and is not illustrated in detail since this type 60 of motor is well known in the art. The

windings 6 and 7 may bear any desired relation to each other. Preferably the high speed winding 6 has a small number of poles, say 4, and the low speed winding 7 has 3 or 4 times that number, say 12 or 16, 70 in order that the winding 7 may give a speed of $\frac{1}{3}$ or $\frac{1}{4}$ of the speed given by winding 6.

The circuit from the turbo-generator 1 to the spinning motor 5 is through leads 8 to a double throw switch 9, arranged to connect leads 8 with either conductors 10, leading to high speed windings 6 of the spinning motor 5 or with conductors 11, leading to the low speed windings 7 of said motor. Current is supplied to the precession motor 3 from the turbo-generator through a circuit comprising leads 8 and conductors 12, which circuit is controlled by a pair of relays 13, 14 for closing and reversing said circuit respectively. The relays 13, 14, are respectively operated by the energization of oppositely wound coils 13', 14', which are both connected at one end to the positive side 15 of a suitable source of direct current. At their opposite ends the coils 13', 14' are connected to the negative side 16 of said source, through a circuit controlled by the auxiliary gyro 4. This gyro is diagrammatically illustrated, the construction and operation 95 of such a device now being well known and shown in the patents above referred to. The circuit of said coils is further controlled by a reversing switch 9'. The switches 9 and 9' are arranged to be latched to each other by a latch 9" so that they may be operated as a single unit or individually. This type of switch is well known and further description of its construction is not believed to be necessary.

The precession motor 3 is provided with a suitable train of gears 17, 18, 19 the latter driving a segmental gear 20 on the main gyro 2. The motor drives said gears through a clutch 21, controlled by an electromagnet 22, connected across the conductors 12 by conductors 23, 24. The circuit comprising conductor 23, electromagnet 21 and conductor 24 is controlled by a relay 25, which in turn is controlled by the auxiliary gyro 4. The construction of the precession motor 3 which is of the A. C. induction type, is not shown in detail, as it is well known in the art.

Having described the principle elements of my invention, its operation will be readily understood from a brief description.

Assuming that it is desired to start the main gyro rotor, the switch 9 will be thrown to connect conductors 8 and 11, in which case the low speed windings 7 are connected to the source and the rotor is started at low speed. The switch may now be thrown to connect conductors 8 with 10, in which case the high speed windings 6 of the

spinning motor are connected to the source, and the rotor is driven at high speed. A switch 26 has been provided to render the auxiliary gyro 4 inoperative, when desired, 5 which of course must be closed.

Should it now be desired to operate the main gyroscope as a stabilizer, in which case its rotor may be driven at either high or low speed, the switch 9 is thrown to connect either the high or low speed windings with turbo-generator 1, as the case may be, and the switch 9' is thrown upwardly to close the circuit controlled by the auxiliary gyro 4 for stabilizing. Of course, the switch 10 26 is now also closed since the main gyro rotor when stabilizing is normally run at high speed and it is found desirable to connect the auxiliary gyro 4 for stabilizing simultaneously with the starting of the main gyro rotor, the switches 9 and 9' are latched to each other so that by one movement they 15 may be thrown upwardly simultaneously to close the circuit of the high speed winding of the spinning motor 5 and to close the 20 circuit of the auxiliary gyro 4 for stabilizing. Assuming that the roll of the ship is such as to precess the gyroscopes to the right. In this case, the auxiliary gyro 4 closes the circuit of coil 13' thereby actuating 25 relay 13 to close the circuit from the turbo-generator to precession motor 3, which drives the gear 19 anti-clock-wise to accelerate the precession of gyroscope 2. It is understood that the relay 25 has been closed by 30 the precession of the auxiliary gyro 4, thereby energizing magnet 22 to operate the clutch 21, in a well known manner. As the ship tends to roll in the opposite direction, the control gyro 4 will precess to the left, 35 thereby opening the circuits of relays 13 and 25, and clutch 21 is released. Continuing its precession to the left, the auxiliary gyro 4 closes the circuits of relays 14 and 25. The latter relay again closes the circuit of 40 magnet 22 to actuate clutch 21 as in the previous case, however, the relay 14 reverses the circuit from the turbo-generator to precession motor 3, which now operates to accelerate the precession of the main gyroscope 2 45 in the opposite direction. This cycle of operations is repeated so long as the main gyro 50 scope 2 is operated as a stabilizer, and as previously stated, it may be so operated while the rotor is running at either its high or low speed.

Should it be desired to employ the apparatus described to roll the ship, the main gyroscope must be precessed oppositely to its normal precession due to the rolling of the ship, that is, the precession motor 3 must now precess the main gyroscope exactly opposite to the direction in which it precessed when used as a stabilizer. In the latter case, 60 since the precession motor was precessing the main gyroscope in its normal direction

of travel, the load on the precession motor was not so great, and it could operate with the main gyro rotor running at full speed. But in the present case, since the precession motor must overcome the gyroscopic forces, 70 it is necessary to reduce the speed of the rotor, and it is accordingly run at its low speed. Since the precession motor 3 must now operate in the opposite direction, the operating of relays 13 and 14 is reversed, 75 through the reversing switch 10. The switches 9 and 9' may be thrown downwardly simultaneously by a single operation to reverse the circuit controlled by the auxiliary gyro 4 and to close the low speed circuit 80 of the main gyro. The switches 9 and 9' having thus been moved to make the necessary connections for rolling the ship, the operation of the several relays and auxiliary gyro is similar to that described for stabilizing the ship. Should the ship be in stable equilibrium, the rolling operation may be commenced by manually precessing the auxiliary gyro 4. It will be observed that, during the rolling operation, while a fraction 85 of the current is continuously supplied to the main gyro, the full current is simultaneously supplied to the precession motor 3, which is now operating under its greatest load. When the precession motor starts, the 90 heavy starting current causes a reduction in the current to the spinning motor, without perceptibly affecting the rotor which continues to spin as a fly-wheel. At the end of the precession movement of the main gyro 100 2, the precession motor may be used as a dynamic brake, thereby increasing the current to the spinning motor.

While I have described my invention as embodied in concrete form in accordance 105 with the provisions of the patent statutes, it should be understood that I do not limit my invention thereto, since various modifications thereof will suggest themselves to those skilled in the art without departing 110 from the spirit of my invention, the scope of which is set forth in the annexed claims.

Having described my invention, what I claim and desire to secure by Letters Patent is:

1. In a gyroscopic stabilizer for ships, the combination with the rotor of the gyroscope, of a multiple speed alternating current induction motor for spinning said rotor at multiple speeds and means whereby the rotor may be driven continuously at one speed for rolling the ship and at a different speed for stabilizing the ship.

2. In a gyroscope the combination with the rotor, of a multiple speed induction motor for spinning the same, means for starting said rotor on a low speed winding and means for running said rotor on a high speed winding.

3. In combination, a source of electric

energy, a gyroscope driven thereby, means whereby said gyroscope may be driven at different speeds, a precession motor driven by said source for precessing said gyroscope, and means whereby said gyroscope may be driven at either of its speeds while the precession motor is driven at full voltage.

4. The combination with a ship, of power means, a gyroscope driven thereby, means whereby said gyroscope may be driven at different speeds, a motor driven by said power means for precessing said gyroscope either to stabilize or roll the ship, and means whereby said gyroscope may be driven at either of its speeds while said motor is driven at full speed.

5. In combination with power means, a gyroscope driven thereby and means whereby said gyroscope may be driven at different speeds, a motor driven by said power means for accelerating the normal precession of said gyroscope or for precessing said gyroscope oppositely to its normal precession, and means intermediate said power means and said gyroscope whereby said gyro driving means may be controlled.

6. In combination, a gyroscope having a multiple speed induction motor, a source of alternating current therefor, a motor for precessing said gyroscope driven by said source, and means intermediate said source for controlling the direction of said latter motor and operating it at full speed while said multiple speed motor is operated at any of its speeds.

7. A rolling device for ships comprising in combination a gyroscope having a multiple speed spinning motor mounted on said ship, a motor for precessing said gyroscope, a source of alternating current for said motors, an auxiliary control gyroscope, and means intermediate said second motor and said source of current controlled by said auxiliary gyroscope whereby said second motor may be run in either direction at full voltage while said spinning motor is run at either of its speeds.

8. A rolling device for ships comprising in combination a main gyroscope having a high and low speed spinning motor, a motor for precessing said gyroscope, a source of current for said motors, an auxiliary control gyroscope, and means controlled by said auxiliary gyroscope whereby said second motor will move the main gyroscope in a direction to roll the ship while its spinning motor is running at low speed.

9. In combination, a gyroscope having a multiple speed induction motor, a source of

alternating current therefor, a motor for precessing said gyroscope driven by said source and means for simultaneously controlling the connection between said motors and said source.

10. In combination, a gyroscope having a high and low speed spinning motor, a source of alternating current therefor, a motor for precessing said gyroscope driven by said source and means for simultaneously closing the high speed circuit of said spinning motor and the circuit of said precession motor.

11. In combination, a gyroscope having a high and low speed spinning motor, a source of alternating current therefor; a motor for precessing said gyroscope driven by said source and means for simultaneously closing the low speed circuit of said spinning motor and reversing the circuit of said precession motor.

12. In combination, a gyroscope having a high and a low speed spinning motor, a source of alternating current therefor, a motor for precessing said gyroscope driven by said source and means for simultaneously closing the high speed circuit of said spinning motor and the circuit of said precession motor in one position, and simultaneously closing the low speed circuit of said spinning motor and reversing the circuit of said precession motor in another position.

13. The combination with a ship of power means, a gyroscope driven thereby, means whereby said gyroscope may be driven at different speeds, a motor driven by said power means for precessing said gyroscope either to stabilize or to roll the ship and means for simultaneously controlling both of said motors to stabilize the ship or to roll the ship.

14. The combination with a ship of a gyroscope for stabilizing or rolling the same having a high and low speed spinning motor, a source of alternating current therefor, a motor for precessing said gyroscope driven by said source and means for simultaneously connecting the high speed winding of said first motor and the precession motor to said source in one position to stabilize the ship, and in another position connecting the low speed winding of said first motor and reversing the circuit of the precession motor to roll the ship.

In testimony whereof I have affixed my signature.

SHIERFIELD G. MYERS.
